UNITED STATES PATENT OFFICE.

FREDERICK A. HAVENS, OF WETHERSFIELD, CONNECTICUT.

END-GATE FASTENING.

SPECIFICATION forming part of Letters Patent No. 502,095, dated July 25, 1893.

Application filed March 22, 1893. Serial No. 467,143. (No model.)

To all whom it may concern:

Be it known that I, FREDERICK A. HAVENS, of Wethersfield, in the county of Hartford and State of Connecticut, have invented certain 5 new and useful Improvements in End-Gate Fastenings; and I do hereby declare the following to be a full, clear, and exact description of the invention, such as will enable others skilled in the art to which it pertains to make 10 and use it, reference being had to the accompanying drawings, which form a part of this specification.

My invention relates to an improvement in end gate fastenings, and the object of the same 15 is to provide a fastener which is carried by the gate and which will automatically engage the wagon body when the gate is closed.

Referring to the accompanying drawings— Figure 1, is a side elevation of the rear portion of a wagon body showing the end gate 20 held closed by my improved device. Fig. 2, is a similar view the latch being raised from the notch of the body. Fig. 3, is rear elevation.

25 A designates the side of the wagon body having near its rear end the transverse groove B, and C designates the end gate. Secured to the outer side of the end gate is the strap D having the perforated projecting lugs E.

30 F is the latch proper having at its rear end the depending lugs G, which are in line with the lugs E, and extending through all these lugs is the pivotal pin H. Encircling this pin between lugs E, is the coiled spring I, one end 35 of which depends on the strap D, while its opposite end is projected upward and a short distance over the latch F, as shown, so as to hold the same normally down, as will be readily understood.

40 The latch at its forward end has the depending lug J, which when the gate is closed is adapted to engage the groove B of side A, and thus hold the gate securely locked, as shown in Fig. 1. An ear K projects from the upper

side of the latch for the purpose of conveniently raising the same when the gate is to be lowered. The coiled spring holds the latch normally down flatly upon the top edge of the gate, as shown in Fig. 2, and when it is pushed forward over the body side A, it is raised 50 slightly but dropped into the groove B, as soon as the latter is reached, thus automatically locking the gate.

My improved locking device is very simple and cheap in construction, while at the same 55 time it is very durable and accomplishes very effectually the desired end.

Having thus fully described my invention, what I claim, and desire to secure by Letters Patent, is—

1. The combination of a body, a hinged end gate, a strap secured thereto, perforated lugs projecting from the strap, a latch adapted to engage the body at its forward end, lugs depending from the rear end of the latch, and 65 a bolt extending through the lugs of the latch and strap, substantially as shown and described.

2. The combination of a body having the transverse groove, a swinging end gate, lugs 70 projecting outward therefrom, a horizontal latch, a lug depending from the forward end of the latch which enters the said transverse groove, depending perforated lugs on the rear end of the latch, a pivotal bolt extending 75 through the last named lugs and the lugs projecting from the gate, and a spring coiled about the said pin having its lower end turned outward to engage the gate and its upper end so projected as to bear against the latch, substantially as shown and described.

In testimony whereof I affix my signature in presence of two witnesses.

FREDERICK A. HAVENS.

Witnesses:

FRED D. GLAZIER,
E. L. WEAVER.
